UNITED STATES PATENT OFFICE.

JAMES F. LANGSTON, OF LANCASTER, CALIFORNIA, ASSIGNOR OF ONE-THIRD TO
ALBERT BULLOCK, OF LOS ANGELES, CALIFORNIA.

CABINET PLUMBING.

Application filed August 3, 1922. Serial No. 579,371.

To all whom it may concern:

Be it known that I, JAMES F. LANGSTON, a citizen of the United States, residing in Lancaster, county of Los Angeles, State of California, have invented new and useful Improvements in Cabinet Plumbing, of which the following is a specification.

This invention relates to various plumbing fixtures, such for instance, as toilets, sinks, lavatories, etc.: and a primary object of the invention is to provide for placing such fixtures out of sight and out of the way when not in use. It is not only an object to put the toilet for instance, out of sight when not in use but also to take it out or move it out of a bathroom, for instance, and thus make more floor space available for general usage. This is also true of sinks, lavatories, etc.

The advantages flowing from the accomplishments of such objects of invention will be readily understood without the necessity of my explaining in detail just how the invention is applied to its various cases.

Accordingly, as illustrative of the invention, I explain it in connection with a toilet and in connection with a sink. Also it will be readily understood that the space into which the article is put when not in use may be a space enclosed within a special structure, as for instance, a special cabinet built for this purpose; or it may be a space within a wall or other part of the building structure; or it may be a space provided partially in both of these ways. As a matter of illustration of my invention I show the two articles herein described as being normally housed in a wall space.

With these preliminaries in mind the invention will be best understood from the following detailed description of illustrative and specific forms of devices that embody the invention, reference for this purpose being had to the accompanying drawings in which—

Fig. 1 is a vertical section showing a toilet mounted in a wall space;

Fig. 2 is an enlarged transverse section taken as indicated on line 2—2 of Fig. 1;

Fig. 3 is a plan taken as indicated by line 3—3 of Fig. 1;

Fig. 4 is an enlarged sectional detail taken as indicated by line 4—4 on Fig. 2;

Fig. 5 is a plan showing a sink installed in accordance with my invention in a wall and

Fig. 6 is a vertical section on line 6—6 of Fig. 5 showing a sink in its normal position in a wall space.

In the drawings, referring first more particularly to Figs. 1 to 4, the letter S represents the wall space within which the bowl B is adapted normally to stand, the two opposite sides of the wall being shown at 11 and 12. There is an opening O through the wall face 12 that is normally closed by a suitable closure, as by a small panelled door 13, and the opening may be surrounded by any suitable case or trim as shown at 14; and all of these features may be so designed and constructed as to harmonize with the interior finish of the room and so as effectively to conceal the fixture.

The outlet pipe for the bowl is shown at 20 leading to a trap 21 and thus connecting with the sewage system. The inlet pipe is shown at 22. These two pipes extend in a horizontal direction and are arranged on a common horizontal axis. The outlet tube 23 of the bowl connects by a swivel joint 24 with outlet pipe 20. This swivel joint may be of any kind suitable for the purpose; for instance, I show a packed joint; and it will be readily understood how this kind of joint allows the bowl to move between the positions shown in full and dotted lines in Fig. 1.

At the inlet side a similar swivel joint 25 is used connecting the inlet tube 26 with inlet pipe 22. The supporting bearings for the bowl may be provided in any suitable manner. They may be provided by bearing supports that are independent of the inlet and outlet pipes, or they may be provided through the medium of the pipes themselves. For instance, at the outlet pipe I show the bowl outlet tube 23 having a supporting bearing in a bearing sleeve 27 that is connected with outlet pipe 20 and may be said to form a part of the outlet pipe, and the outlet pipe and this part 27 are supported by a supporting bracket 28 resting upon floor F. At the inlet pipe I show inlet tube 26 having a direct bearing in supporting bracket 29 which stands upon the floor. In either case it will be seen that the bowl can

turn about the axis of the two pipes and that, whatever the position of the bowl the connection to both pipes is maintained.

The bowl here shown is preferably of a special construction, to be of as small depth as practicable and to provide for getting the flushing water from the inlet pipe up to the upper edge of the bowl. Around the inner upper edge of the bowl there is formed a water channel 30 with a continuous opening or slot at 31 to discharge water at the upper edge of the bowl wall; and a passage 32 leads from inlet tube 26 to this channel 30. The bowl is so constructed that its lowermost part, when in either position leads directly into the outlet tube 23 as can be seen from consideration of Figs. 1 and 2; so that the bowl can be completely flushed. The outlet and inlet tubes and pipes are located in a position that may be described as being in the lower back corner of the bowl when the bowl is in the position shown in dotted lines in Fig. 1. The bowl also has a top wall 35 that extends a little distance forward from its rear end, so that when the bowl is in the position shown in full lines in Fig. 1, it will still hold water up to the trap level. This prevents any flow of water out of the bowl when the bowl is put back into the wall; and a small guard wall at 36 prevents any water being splashed out of the bowl as it is put back into normal position.

When the bowl is down, in the position shown in dotted lines in Fig. 1, it may be supported by any suitable supporting means. Various such means may be used; I here merely show a simple supporting means that is formed by the door 13 resting on what is in effect the base board, or bottom board of the casing or trim, as shown at 40.

I prefer, in my installation as here described, to use an automatic flushing valve that may be placed in water pipe 41 as indicated at 42. The stem 43 of this valve may project inwardly toward the bowl and there be provided with a handle 44 for its operation to supply flushing water. I also provide automatic means to flush the bowl automatically when it is put back to its normal position. This means may, for instance, be supplied in the manner shown in detail in Fig. 4.

An arm 45 is mounted on the tube 26 and swings with that tube when the bowl is swung between its two positions. This arm carries at its outer end a pawl 46 that is normally held in the position shown in Fig. 4 by a suitable spring 47, a stop 48 serving to limit the spring pressed movement of the pawl. As the bowl is put back into the wall this pawl 46 catches on an arm 48 that depends from valve stem 43, and as the pawl swings toward the position shown in dotted lines in Fig. 4, the arm 48^a is moved back to the position shown in dotted lines. At

this position the pawl passes beyond the arm; and the subsequent automatic action of the flushing valve 42 throws the arm 48, and the handle 44, back to the position shown in full lines in Fig. 4, when the predetermined quantity of water has been supplied to the bowl. When the bowl is again lowered, the pawl 46 wipes under the arm 48^a and then springs up to the position shown in full lines in Fig. 4 ready for the next automatic operation of the flushing valve when the bowl is put back in the wall. Thus I provide not only a means whereby the bowl may be flushed at will, but also a means whereby the bowl must necessarily be flushed as it is put back in the wall.

In Figs. 5 and 6 I show the same scheme applied to a sink or similar article. The sink is shown at 50; the drain pipe at 51, and the water inlet pipe at 52. The valve 53, controlling the water supply, may have a handle 54 extending out through the wall face 12, in a position close to the sink. Inlet and outlet tubes 26 and 23 may be supported in bearing brackets 29 and 28. The swivel joints are shown at 24 and 25. The inlet and outlet pipes are here, as in the other construction, mounted on a common horizontal axis and are located at the lower back corner of the sink, as is apparent from Figs. 5 and 6. The door 13, attached to the bottom of the sink, closes the wall opening when the sink is in the wall space. The wall supply to the sink may of course flow directly onto its bottom through inlet 26. Or I may use a small water spout 30^a connected to the water passage 32 which connects with water inlet 26; to supply water at or near the upper edge of the sink in a convenient position for such operations as are usually carried on in a sink.

Having described a preferred form of my invention, I claim:

1. In combination, a tiltable bowl, inlet and outlet pipes therefor located on a common horizontal axis, swivel joints between the bowl and pipes so that the bowl may tilt on the pipe axis between a substantially horizontal and a substantially vertical position; a trap in the outlet pipe, and the rear end of the bowl having a wall that forms with the bottom and back wall, when the bowl is tilted up, a water container that holds water at a level as high as the trap level.

2. In combination, a tiltable bowl, inlet and outlet pipes therefor located on a common horizontal axis, swivel joints between the bowl and pipes so that the bowl may tilt on the pipe axis between a substantially horizontal and a substantially vertical position; a valve controlling the inlet pipe, and automatic means to operate the valve as the bowl is swung to vertical position; a trap in the outlet pipe, and the rear

- end of the bowl having a wall that forms with the bottom and back wall, when the bowl is tilted up, a water container that holds water at a level as high as the trap level.
- 5 3. In combination, an open topped water containing member adapted to swing between substantially horizontal and vertical positions, an inlet and an outlet pipe on a common horizontal axis located and connected to the member near its back lower corner, swivel connections between the member and the two pipes on which swivels the
- 10 member swings, and means to control admission of water to the member through the inlet pipe when the member is in either of its positions, the rear end of the member having an upper wall that forms with the bottom and back wall, when the member is tilted up, a water containing chamber.
- In witness that I claim the foregoing I 20 have hereunto subscribed my name, this 27th day of July, 1922.

JAMES F. LANGSTON.
